UNITED STATES PATENT OFFICE.

FREDERICK R. HIRSH, OF NEW YORK, N. Y.

DESIGN FOR A KNOB.

SPECIFICATION forming part of Design No. 24,781, dated October 22, 1895.

Application filed June 26, 1895. Serial No. 554,150. Term of patent 7 years.

To all whom it may concern:

Be it known that I, FREDERICK R. HIRSH, a citizen of the United States, and a resident of the city of New York, in the county and State 5 of New York, have invented and produced a new and original Design for Knobs, of which the following is a specification, reference being had to the accompanying drawing, forming a part thereof.

10 The drawing is a front view of a knob, showing my design.

The leading feature of my design consists in a pointed Romanesque leaf lapping the periphery of the knob in such a manner as to 15 leave an open space or plain panel, in which any desired lettering may be placed.

The drawing represents a knob having a large central plain panel embraced by a Romanesque leaf located on the periphery of the knob, thus forming an ornamental frame 20 to the plain panel.

Having thus described my invention, the following is what I claim as new therein and desire to secure by Design Letters Patent:

The design for knobs, substantially as 25 herein shown and described.

FREDERICK R. HIRSH.
